APPARATUS FOR CAPPING BOTTLES

Edward N. Winslow, Shaker Heights, Ohio, assignor to E. I. du Pont de Nemours & Company, Wilmington, Del., a corporation of Delaware

Application April 1, 1937, Serial No. 134,284

2 Claims. (Cl. 226—80)

This invention relates to packaging and is particularly concerned with an apparatus for applying elastic caps to bottles.

Rubber caps not unlike a thimble in shape and provided with a heavy bead at the open end are commonly applied to glass-stoppered bottles used in the chemical industry for packaging corrosive liquids. Caps of this type are used primarily to hold the stopper in place and to protect the sealing medium used to seal the juncture of the stopper and the bottle.

The advantages offered by the use of the rubber cap, however, have been considerably offset by the difficulty of applying the cap. When the operation was effected by hand, injury and discomfort to the operator resulted. Even when hand application was aided by the use of such apparatus as was heretofore available the task was onerous and difficult. Furthermore, the cap was rarely applied evenly as it was inordinately difficult so to apply it.

It is an object of this invention to provide an apparatus for applying elastic caps to bottles, which apparatus is effective and economical and easily and simply operated and carried out; wherein the necessity of manipulating the cap into place by the fingers of the operator is avoided, and; wherein the cap is applied evenly and uniformly to the bottle. Further objects will be apparent hereafter.

In the accompanying drawings:

Fig. 1 is an axial section of my capping mechanism in the closed position, showing a rubber cap in place prior to expanding it for application to the bottle;

Fig. 2 is a similar view of the expanded position showing the first stage of the application of the expanded cap to the bottle;

Fig. 3 is a similar view showing an intermediate position in the application of the rubber cap.

Fig. 4 is a similar view showing the final position with the cap applied;

Fig. 5 is a fragmentary section taken in line 5—5 of Fig. 7;

Fig. 6 is a plan view showing my capping mechanism in the closed position, and;

Fig. 7 is a plan section taken on line 7—7 of Fig. 1.

As shown in the accompanying drawings, my apparatus consists of a plurality of circularly arranged upright fingers 1 adapted to be positioned within the open end of a rubber cap and means for radially expanding these fingers in such a manner that the rubber cap may be ex-

panded sufficiently freely to encompass the neck of the bottle.

The fingers 1 form a unitary part of the L-shaped finger slides 2 which are confined to radial movement by the radial channel guides 3 formed between the radially-channelled, annular guide plate 4 and the annular base plate 5. The plates 4 and 5 are fastened together by the headed fasteners 6 which are threaded into the annular buffer-ring 7, the whole forming an assembly 8 in which the finger slides 2 are slidably mounted.

By this construction, the slides 2 are confined to radial movement so that the fingers 1 may be positioned in either of the positions illustrated in Figs. 1 and 2 at will. In order that the closed position of Fig. 1 may be the normal one, I provide an elastic band 9 arranged to urge the slides inwardly as shown in Figs. 6 and 7.

Actuation of the finger slides 2 is effected by means of links 10 pivotally connecting the ends 20 of the slides 2 to the axially movable top plate 11. The outer ends of the links are journaled in housings 12 at the ends of slides 2 and the inner ends of the links are similarly journaled in the housings 13 equally spaced on the top plate 11. 25

Raising the top plate 11 causes the slides 2 to move inwardly so that the fingers 1 move to the closed position illustrated in Fig. 1. Pressing the top plate toward the assembly 8 causes the slides 2 to move outwardly so that the fingers 1 move 30 to the expanded position illustrated in Fig. 2. Thus it may be seen that the fingers 1 may be moved from the position shown in Fig. 1 to that shown in Fig. 2, without disturbing the relative circular arrangement, by simply pressing the top 35 plate 11 toward the assembly 8. Movement in this manner from a small circle of arrangement to a larger circle of arrangement makes it possible to expand the rubber cap uniformly about its periphery sufficiently freely to encompass the neck 40 of the bottle.

Once the top is expanded as illustrated in Fig. 2, it may be applied by a simple downward thrust. In this manner, the fingers are withdrawn from the cap but not until the bead 14 has been pulled 45 down to a point sufficiently below the shoulder 15 to allow it to snap snugly into place beneath the shoulder. Successive positions during this operation are illustrated in Figs. 2, 3 and 4.

Thus Fig. 2 shows the initial position with the interior apex 16 of the cap engaging the top of the stopper 17; Fig. 3 shows an intermediate position with the walls of the cap engaging the lip 18 of the bottle; and Fig. 4 shows the final 50 55

position with the bead 14 snugly engaging the shoulder 15.

It may be observed that between the initial position and the intermediate position shown in Figs. 1 and 2, respectively, the pressure on the top plate 11 has been released so that the fingers 1 engage the neck of the bottle. In this manner the clearance between the cap and the neck of the bottle is reduced to a minimum so that the fingers may be withdrawn more easily. Likewise, the spacing between the bead 14 and the neck of the bottle is uniformly maintained.

As the downward movement continues from the position shown in Fig. 3 toward the position shown in Fig. 4, the cap is stretched further. Due to the frictional engagement of the walls of the cap with the lip of the bottle, however, this stretching is confined to the portion of the cap, as shown in Fig. 3, that is between the bead 14 and the lip 18 of the bottle. The stretching of this portion of the cap continues until the bead is well below the shoulder 15.

At the same time the fingers 1 are being gradually withdrawn. By the time they are completely withdrawn, however, the bead 14 will have been drawn sufficiently below the shoulder 15 to snap automatically into place beneath the shoulder. This action is facilitated by the fact that the fingers 1 move inwardly as they slip past the shoulder 15 so that the tension of the bead 14 is further reduced.

The tool is removed, after completion of the application of the cap in Fig. 4, by compressing plate 11 to position as shown in Fig. 2. In this position the fingers clear the outside of the cap over the lip 18.

It is to be understood that no means is relied upon for pulling the bead 14 to a point below the shoulder 15 before its release, other than the frictional resistance which the bead offers to the withdrawal of the fingers 1. The force which counteracts this frictional resistance is engendered by the stretching of the portion of the cap, as shown in Fig. 3, that is below the lip 18.

It will be readily apparent that the length of this portion of the cap may be varied by varying the length of the fingers 1. Thus the longer the fingers, the farther the bead 14 may be stretched below the shoulder 15 before it is released. If the fingers 1 are too short the bead will be released too quickly so that it will not be properly seated below the shoulder; if they are too long the bead will not be released because the downward movement of the assembly 8 is limited by the bottle proper.

I have found that the best results are obtained when the length of the fingers 1 is approximately equal to the height of the shoulder 15 plus the height of the bead 14.

It may be seen from the above that once the cap is placed over the fingers, as shown in Fig. 1, it may be applied by simply pressing the top plate 11 toward the assembly 8, positioning the interior apex of the cap upon the top of the stopper, and pushing the assembly downward. The entire operation, even in the hands of a novice, requires not more than a few seconds and involves no hand manipulation of the cap whatsoever. Hence the bottles may be capped more rapidly than heretofore and without personal injury or discomfort to the operator.

Not only is the necessity of hand manipulating of the caps eliminated by my processes and apparatus but also the necessity for hand manipulation of the bottles. Whereas it has heretofore

been necessary to remove the bottles from the truck upon which they are conveyed to a suitable work table to give the operator ample room for applying the cap, it is now possible by the use of my processes and apparatus to cap the bottles without removing them from the truck as the outside diameter of my apparatus freely clears adjoining bottles nested on the production truck. In actual plant scale operations the gross time required for the application of the cap has been reduced by fifty per cent.

Another factor of importance is the reduction in the breakage hazard. By the elimination of the necessity for removing the bottle the possibility of breakage by dropping is eliminated.

Although I have mentioned that it is desirable to release the top plate 11 once the cap is in position, as shown in Fig. 2, it is to be understood that this is not essential. The entire operation may be satisfactorily carried out with the top plate 11 tightly pressed against the assembly 8. Operation in this manner is not so desirable, however, because in the first place more force is required to withdraw the fingers and in the second place the clearance illustrated in Fig. 2 permits of lateral movement that may cause non-uniform spacing of the bead 14 about the neck of the bottle.

Due to the fact that the assembly 8 may strike the bottle proper with considerable force when the cap is released, it is desirable to provide the buffer ring 7. It is to be understood, however, that the buffer ring is purely a safety device and consequently not essential to the operation of the apparatus. When employed, however, its thickness and diameter should be so correlated to the curvature of the bottle, as shown in Fig. 4, so that the downward movement of the assembly 8 is interrupted substantially at the point of release. In this manner rugged material, such as fiber or hard rubber, that has relatively slight shock absorbing properties may be successfully used.

Although I have illustrated six fingers in the drawings it is apparent that any larger number, within the limits of mechanical practicability, may be employed. A substantially smaller number should be avoided, however, as it is apparent that the smaller the number of fingers the less uniform the expansion of the cap. I do not wish to be restricted to six, however, as five may be used with good results and even three or four may be used acceptably.

The essential feature of my apparatus resides in the fingers 1 which are adapted to be inserted within an unexpanded cap and to expand the cap sufficiently for it freely to encompass the neck of the bottle. It will be apparent therefore that any suitable means may be employed for moving these fingers. Although I have disclosed a plurality of sliding members 2 for this purpose, it will be readily apparent to those skilled in the art that various mechanical movements may be used for spreading the fingers such as pivoted members.

A particular advantage of the construction illustrated, however, resides in the mechanical advantage obtained in moving the top plate 11 from the position of Fig. 1 to that of Fig. 2. In the latter position it may be observed that the links 10 are sufficiently close to a position of static equilibrium that only slight pressure on the top plate 11 is required to maintain the expanded condition against the tension of the rubber cap. The links could be so arranged that static equilibrium would be obtained but this is

undesirable because, as previously pointed out, better results are obtained when the top plate is released between the position of Figs. 2 and 3.

Although I have shown and described my apparatus as particularly adapted to the application of rubber caps to C. P. acid bottles of the type illustrated, it is apparent that it may be used to apply elastic caps of various types to various bottles. It may be used, for example, in applying relatively shallow rubber caps to milk bottles, although it is apparent that the application of such caps do not offer the same difficulties as the application of the deep cap.

Due to the fact that the drawings have been made from a commercial form of my apparatus, a number of perforations 19 may be observed in the plates 4, 5, and 11. As these perforations are provided mainly for the purpose of reducing the weight of the structure it is apparent they are not essential. They serve to illustrate, however, that the form of the plates 4 and 5 in between the channel guides 3 is relatively unimportant so long as it is such as to maintain the radial position of the channel guides 3 and 3. Thus it will be readily apparent to those skilled in the art that the channel guides 3 may be formed in various ways and that they may be maintained in radial position by suitable connecting structures, whether by the perforated web portions of the plates 4 and 5 as shown, by suitable interconnecting braces or networks or by similar structures, or whether formed of a plurality of discrete plates as shown, as a unitary casting or similar structure.

Although I have disclosed an arrangement wherein the loci of arrangement are circles, it is apparent that the loci of arrangement may correspond to other geometrical figures, the essential feature being that the final or larger loci of arrangement correspond to the shape of the body to which the cap is to be applied. Correspondingly, the inner or smaller loci of arrangement may take any form desired.

It is to be understood that the movement of the fingers from the inner loci of arrangement to the outer may be varied from the manner shown, the essential feature being that the fingers be relatively movable. Thus one or more of the fingers may be fixed and the remaining ones movable relative thereto. For example, in applying elastic caps to elliptical bodies the finger corresponding to the minor axis of the ellipse may be fixed. A similar arrangement may, of course, be used with circular bodies if desired but the cap would have to be stretched across the fixed fingers before it could be expanded.

I claim:

1. In an apparatus for expanding an elastic cap for application to a cylindrical body, a plurality of circularly arranged upright fingers projecting rigidly from the inner end of a plurality of slides confined to radial movement by radial guides, a top plate axially movable with respect to said guides and means connecting the outer end of said slides with said top plate to transmit axial movement of said top plate into radial movement of said slides.

2. In an apparatus for expanding an elastic cap for application to a cylindrical body, a plurality of circularly arranged fingers projecting rigidly from the inner ends of slides confined to radial movement by guides radially mounted on an annulus, a second annulus parallel to and axially movable with respect to said first annulus and link means connecting said second annulus with the outer ends of said slides arranged to transmit axial movement of said second annulus into radial movement of said slides whereby the relative circular arrangement of said fingers is unchanged, the inside diameter of said annuli being greater than the diameter of the largest circular arrangement of said fingers whereby the space interiorly of said fingers is open and unobstructed.

EDWARD N. WINSLOW.
